UNITED STATES PATENT OFFICE.

ALBERT S. ROBINSON, OF ALBANY, NEW YORK, ASSIGNOR OF ONE-HALF
TO ABRAHAM SCHELL, OF SAME PLACE.

BALING-PRESS.

SPECIFICATION forming part of Letters Patent No. 311,680, dated February 3, 1885.

Application filed March 24, 1884. (No model.)

To all whom it may concern:

Be it known that I, ALBERT S. ROBINSON, a citizen of the United States, residing at Albany, in the county of Albany and State of New York, have invented certain new and useful Improvements in Baling - Presses, of which the following is a specification.

My invention relates to that class of baling-presses in which a sweep-lever is employed to imparting to the platen a reciprocating movement; and it consists of the parts and devices and combinations and arrangements of devices, hereinafter fully described and set forth.

The objects of my invention are to provide means for guiding the compressed material from the pressing-chamber through the baling-chamber to its exit without bending or buckling under the pressure of the platen; also, to provide a toothed-gear-lever pressing mechanism which will be cheap in construction, simple in its parts, efficient in operation, and not liable to get out of order, and be operated by the vibrating movement of a sweep-lever; also, to provide mechanism which will hold the sweep-lever from sagging or moving out of a horizontal plane; also, to provide elastic dogs for operating with pressed sections of material to hold the same from moving back; and, further, to provide a friction mechanism which will operate with the sweep-lever at the time of each movement of the same past its point of center of motion, for preventing a rebound of said lever when the platen has finished its full length of forward thrust against the material being compressed. I attain these objects by means of the devices and combinations of devices illustrated in the accompanying drawings, (in three sheets,) forming a part of my specification, in which—

Figure 1 represents a plan view of a baling-press embodying my improvements, two feet of baling-chamber broken out. Fig. 2 is a side elevation of the same. Fig. 3 is a horizontal sectional view, on an enlarged scale, of a side (a section thereof, and showing a retaining-dog) of the press, taken at line 1 1 in Fig. 4. Fig. 4 is a cross-sectional view through a side of the press at line 2 2 in Fig. 2, showing the retaining-dogs on an enlarged scale. Fig. 5 is a plan view of the gear-lever

mechanism for operating the platen on an enlarged scale. Fig. 6 is a rear end elevation of the press. Fig. 7 is a front end elevation of the press. Fig. 8 is a sectional elevation of the friction or brake mechanism for preventing a rebound of the sweep-lever, taken at line 3 3 in Fig. 1 and line 4 4 in Fig. 2; and Fig. 9 is a sectional and detail view of the same, taken at line 5 5 in Fig. 8.

All the above detail views are on an enlarged scale.

The same letters of reference refer to similar parts throughout the several views.

In the drawings, A A represent the bottom sills of the press. A' A' are the top plates; A², the vertical side posts, and A³ the cross-bars. These pieces are joined together, and are securely held together by bolts or in any proper manner, as practiced by the trade, and together form the frame-work of the body of the press.

B is the platen chamber, in which platen P (shown by dotted lines in Fig. 2) is moved in a reciprocating manner, and C is the baling-chamber. The platen-chamber has its vertical and top and bottom sides made close or substantially tight by side linings or boards, as is the practice by the trade, and the top and bottom sides, a a', of the chamber are continued to the baling-chamber and extended to the rear end thereof, as shown by dotted lines in Fig. 2. The portion of top lining, a, forming the top wall of the baling-chamber, is unsupported and disconnected in its entire length from the rear end of the platen-chamber to the rear end of the baling-chamber, so as to be free to be deflected toward bottom lining, a', by means of mechanism heretofore employed by myself and not forming a part of this invention. The sills A A and plates A' A' are made with a greater extension in their vertical direction than in their horizontal direction, as shown in Fig. 6, and top lining, a, is so arranged in relation to plates A' that the lower surfaces of said top lining will be on a horizontal plane about two inches, more or less, above a line, y', drawn with the horizontal plane of the lower side of said top plates. (Illustrated in Fig. 6.) Bottom lining, a', is arranged in such a relation to sills A that the upper surface of said bottom lining will

be on a horizontal plane about two inches, more or less, below a line, y^5 , drawn with the planes of the upper side surfaces of said sills, as shown in the same figure. By these arrangements of the top and bottom linings, aa' , with sills and plates A A', the portions of the inner and oppositely-located vertical sides, $a^2 a^2$, of said sills and plates are made to project inward from the inner side surfaces of the respective linings, and form guides or ways by which the compressed material will be held from buckling in the baling-chambers, and be guided through the same to an exit at the rear end of the press, while at the same time a saving of material and cost of construction is effected.

Located at the end of the platen-chamber B, next to baling-chamber C, and in the side of the press, are a series of elastic retaining-dogs, T T, which work in openings $u u$, made through the side timbers, A ^{2} , and linings of the press and supplemental bar A ^{4} . These dogs are shown in Figs. 3 and 4, and are each provided with a beveled head, t', which are arranged with their straight sides toward the baling-chamber and their bevel running back toward the platen-chamber. These dogs are each made elastic by springs s', steadyng-stems s ^{2} , and held against plate u ^{2} and secured at the outer side by a key, u', as shown, or a nut. Each vertical side of the baling-chamber is provided with a single opening, O, extending horizontal from the rear end of the platen-chamber to the rear end of the baling-chamber, and in a vertical direction from the lower side surface of top plate, A', to the upper side surface of sill A. Through these side openings, O O, a bale may be bound with any desired number of bands in an easy and convenient manner. D is the feed-hopper communicating to the platen-chamber through opening b.

P is the platen. (Shown in dotted lines in Fig. 2.) E is an arm hinged to the rear side of the same; and F F' is a lever hinged to arm E, as shown in Figs. 1 and 2, and actuates said pitman in a reciprocating moving manner, accordingly as said lever is vibrated from its fulcrum d. This lever has its long arm F and short arm F' made, preferably, of a single piece of cast metal, and short arm F' is made in the form of a toothed section of an ellipse, as shown in Fig. 5—that is to say, the said arm is in the form of a section of an elliptical cog-gear, having teeth c, arranged on the face of the rim of the same, as shown. The fulcrum of this lever consists of shaft d, supported in suitable bearings, e e, from the frame of the press. The arm F of this lever practically forms with arm E, hinged to the platen, a toggle-lever.

G G' is the sweep-lever, composed of wood and metal, and mounted on the vertical shaft f, which is held in suitable bearings from the press-frame. The long arm G of the lever projects outward from its fulcrum f and forms the sweep-lever, to which the animal is

hitched for operating the pressing mechanism of the press. The short arm G' of the sweep-lever is made in the form of a section of an eccentric gear, having its cogs or teeth c' corresponding with the cogs or teeth c of short arm F' of the coacting-lever F F'. The fulcrum-shaft f of the sweep-lever G G' is so situated in relation to the toothed surface of short arm G' as to be nearer to the middle of the length of its toothed periphery, which is made on a curve of a true circle, than the terminating ends thereof, as shown in Figs. 1 and 5. The form of construction of the short arms of these two coacting-levers F F' and G G' are peculiar in their relative curvatures of their respective toothed portions. The curvature of arm F' is that of a section of an ellipse with the fulcrum set at a point back from the center of the same to such a distance as to be within the rear end portion of the curve if the ellipse were continued unbroken. The arm G' of the sweep-lever is made in the form of a section of a true circle with the fulcrum at a point eccentrically to the same and near the middle of the length of the curve, and on a line with a line drawn longitudinally through lever g from one end to the other. With these forms of curvatures each half of the whole line of cogs on the elliptical curve of arm F, from y to y', will correspond in length with the length of the whole line of cogs on the true circle curve of arm G' from x' to x ^{2} . Made with these curves, as and with the fulcrum of each set as above described and shown, the teeth of each arm will fully and truly engage with those of the other in their entire length of respective lines. When sweep-lever G is moved in either direction from that shown by full lines to that shown by dotted lines in Fig. 5, the cogged arm G' will operate cogged arm F' of lever F and move it to a corresponding position shown by dotted lines in the same figure, and thereby operate with hinged arm E of platen P to draw it back, and when the sweep-lever G G' is moved back to full lines the arms E and F will be operated substantially as a toggle-lever, with a gradually lessening of speed of forward movement of the platen and a gradually-increasing power.

To prevent the rebound of the sweep-lever, I provide a brake mechanism which will operate to retard the free movement of the same when the toggle-levers E and F are passing from coincident lines of position and the platen is about to be drawn back, and until the platen has ceased to be influenced by the reactive force of the material in the pressing and baling chambers of the press.

This mechanism consists of plate Q, Figs. 7, 8, and 9, having an elastic support at the lower side of bar H by means of upright arms l l, working in vertical ways k k, springs s s, perforated necks m m, and adjustable flanged nuts n n. This plate is prevented from shifting endwise by shoulders j j. This plate is provided at its horizontal sides with ways o o,

Fig. 9, with which ways is arranged the traveling brake-roller R, having its bearing in housing g, provided with flanges o' o'. These flanges of the housing of roller R fit loosely 5 in ways o o of plate Q, and being thus arranged, the said housing and roller will be adapted to be moved in either direction from one end of said plate to the other.

Secured to the upper side of sweep-lever 10 G and beneath plate Q is flat plate g, having its upper surface on a plane above the upper surface of said lever. When the sweep-lever is moved from right to left, the end of plate g will strike roller R on its right-hand side 15 and move it with its housing from position of full lines in Figs. 7 and 8 to position indicated by dotted lines in the same figures, when its further movement will be checked by left-hand side shoulder, j, and the left-hand end of plate g will then pass under roller R and be pressed down on plate g (or sweep-lever G) by the force of springs s s, exerted through plate Q and the connected housing g, and this pressure will be continued until 20 the sweep-lever has been carried to such a distance to the left hand as to carry plate g wholly beneath the roller R and from beneath the same. This pressure of roller R on the sweep-lever when passing beneath the former will 25 effectually check the rebound of the latter. When sweep-lever is reversed, roller R will be carried from its position indicated by dotted lines to that shown by full lines, when the same operation of the parts will be had and 30 the same results will be obtained.

Secured to the frame-work of the press are one upper and one lower circular ways, L L', between which sweep-lever works. These circular ways are preferably made of pieces of 40 timbers cut in sections of a circle and joined together, though they may be made of iron, or iron and wood combined. These ways are plated with circular wear-plates t t, and secured to the lower side of the sweep-lever is 45 a short wear-plate, t', which has bearing on lower wear-plate, t, or lower ways, L'. These ways support the outwardly-extended portion of the sweep-lever from dropping downward and hold the same in one horizontal 50 plane throughout its entire length of movement.

By the above-described improvements I am enabled to produce an effective press, which will not be liable to get out of order and will 55 have its sweep lever prevented from rebounding and annoying the animal operating the sweep, while the bales produced thereby may be tied off with any desired number of bale-bands.

Having described my invention, what I claim, and desire to secure by Letters Patent, is—

1. In a baling-press, an open-sided baling-chamber, C, which is formed by the combination of horizontal sills A A, horizontal plates A' A', and upper and lower horizontal linings, a and a', so arranged that the said linings a and

a' will be set apart from each other and from the facing horizontal surfaces of the sills and plates, respectively, as at dotted lines y⁴ y⁵, so 70 that the surfaces a² a² of said sills and plates will form partial sides to the vertical sides of the baling-chamber, substantially as and for the purposes set forth.

2. In a baling-press, the combination, with 75 the platen provided with hinged arm E, of the lever F F' and sweep-lever G G', the short arm of lever F F' being made with the form of a section of an ellipse, with a fulcrum placed substantially as above described, and the sweep-lever having its short arm made in the form of a section of a circle, with its fulcrum set eccentrically with the same, substantially as above described, and both of said short arms being provided with engaging-teeth on their 85 face surfaces, all for operations substantially as and for the purposes set forth.

3. In a baling-press, the combination, with 90 the press frame and a sweep-lever which turns on a pivot made stationary in the frame for actuating a toggle-lever pivoted to the platen, of sweep-supporting ways arranged one above and one below said sweep-lever, substantially as and for the purposes set forth.

4. In a baling-press, the combination and 95 arrangement, with the press-frame and a reciprocating moving sweep-lever which operates a toggle-lever of the platen of the press, of the circular ways L L', substantially as and for the purpose set forth.

5. In a baling-press, the combination, with 100 the frame-work of the same and a sweep-lever operating a platen by means of a toggle-lever mechanism, of a brake mechanism between said frame-work and the sweep-lever which 105 will operate with the said lever to retard its movements only when the toggle-levers have commenced to assume diverging lines and cease such retarding when the reactive force of the compressed material in the pressing and 110 baling chambers have ceased to effect the platen, for operations and purposes set forth.

6. In a baling-press, the combination, with 115 piece H, of the frame and sweep-lever operating a toggle-lever mechanism which works the platen, of a brake-roller which is revolved under pressure only when it is running on and across the sweep-lever or a plate attached thereto, and while the toggle-levers are affected by the reactive force of the compressed material in the pressing and baling chambers.

7. In a baling-press, the combination, with 120 piece H, and the sweep-lever operating a toggle-lever mechanism, of a traveling roller, R, adapted to be moved both directions to stops j, and an elastic pressing mechanism operating to force said roller down on the sweep-lever or a piece attached thereto only after the sweep-lever has passed a line coincident with the lines of the toggle-levers operating the 125 platen, and until the compressed material has ceased to react against said toggle-levers, substantially as set forth.

8. The combination, with sweep-lever G, pro-

vided with plate *g*, and the plate *Q*, provided with ways *o*, working between shoulders or stops *j*, and provided with arms *ll*, working in seats *m m*, of springs *s s*, flange-nuts *n n*, 5 and traveling roller *R*, mounted in a housing working in ways made in the plate *Q*, substantially as and for the purposes set forth.

9. In a baling-press, the combination, with the press-frame and a sweep actuating a pressing mechanism, of a friction device which will be stopped to a short distance by the action of the sweep toward the side to which the sweep is being moved, and in this shifted position operate with the sweep until it has moved fully 15 past its center of motion, substantially as and for the purposes set forth.

10. In a baling-press, the combination, with the platen, toggle-lever operating said platen, sweep-lever actuating said toggle-lever, of an elastic way supported from the press-frame, a traveling friction - roller working with said way, and a friction plate secured to the sweep-lever, for operation substantially as set forth. 20

11. The combination, with sweep-lever provided with a variable short arm having teeth, 25 and toggle-lever pivoted to the platen, with a lever thereof provided also with a variable short arm, also having teeth, of a friction-plate secured to the sweep-lever, and a friction-roller supported from the frame and operating with the friction-plate when the variable short arms of said levers are passing their centers, substantially as and for the purpose set forth. 30

12. In a baling-press, the combination, with retaining-dogs provided with springs, of supporting-stem *s*, plate *u*, provided with perforations or bearings for freely receiving said supporting-stem pin, and a key, *u'*, or its equivalent, substantially as and for the purpose set forth. 35
